CONVERTER

James Teague, Chicago, Ill., assignor to Industrial Development Engineering Associates, Inc., Indianapolis, Ind., a corporation of Indiana

Application July 2, 1956, Serial No. 42,103

Term of patent 14 years

(Cl. D26—14)

FIG.1

FIG.2

FIG.3

Fig. 1 is a perspective view of a converter showing my new design;

Fig. 2 is a front view thereof; and

Fig. 3 is an end view.

The dominant features of my new design are shown in solid lines in the drawing.

I claim:

The ornamental design for a converter, as shown and described.
